UNITED STATES PATENT OFFICE.

JAMES M. LAWLOR, OF TOPEKA, KANSAS, ASSIGNOR OF ONE-HALF TO T. H. CUTSINGER, OF TOPEKA, KANSAS.

OPTICIAN'S TOOL.

1,415,659.

Specification of Letters Patent.

Patented May 9, 1922.

Application filed October 1, 1920. Serial No. 414,035.

To all whom it may concern:

Be it known that I, JAMES M. LAWLOR, a citizen of the United States, residing at Topeka, in the county of Shawnee and State 5 of Kansas, have invented certain new and useful Improvements in Opticians' Tools; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to opticians' tools and particularly to a tool adapted to be used as a pincers or clamp for assembling eye-glass mountings, for effecting adjustments and for use in connection with the 20 general organization of such mountings, and particularly for remounting and replacing lens frames.

It is the purpose of my invention to provide a tool which is capable of effectively 25 crimping or pinching the rim clamps at the ends of the bridge piece to the lens frames in such a manner that a tight union will be provided without liability of crushing the edges of the lenses.

30 It is also the purpose of my invention to provide an improved tool which is adapted to be utilized as a hand clamp for efficiently holding the mounting so that the bridge may be bent to provide the proper adjustment to 35 suit the user, the device being also capable of holding the mounting in clamped position for effecting the requisite adjustments and assembly of the nose clamp, finger pieces, etc.

40 The invention also contemplates the provision of means for adjusting the limits of movement between the clamping jaws to provide for various thicknesses of the material to be held between them, this being 45 important when the jaws are brought together.

Other objects of the invention will be referred to hereinafter, it being understood that changes in form, proportion and minor 50 details of construction may be resorted to without departing from the spirit of the invention or sacrificing any of its advantages.

In the drawings,

Fig. 1 is a perspective view of a tool 55 constructed in accordance with my invention.

Fig. 2 is a vertical, sectional view through the handle grips, the jaws being shown in elevation.

Fig. 3 is a perspective view of the jaws. 60

Fig. 4 is a perspective view of the upper portion of the tool, showing it in operative position.

Fig. 5 is a detached view of a mounting, part of a lens and frame being shown ready 65 to be engaged by the terminal clamps on the ends of the bridge, and

Fig. 6 is a perspective view of an expanding tool, a supplemental jaw being shown in removed position. 70

Referring now to the drawings by numerals of reference:

1 designates a rigid jaw at one end of an elbow lever 2, the lower end of the elbow lever extending at an obtuse angle to the 75 jaw 1 and having at its lower extremity a pivoted handle grip 3, fastened thereto by a fastening device shown as a screw 4, whereby it is adapted to rock with respect to the lever 2. The upper end of the grip is provided with a perforation 5, through which projects a threaded stud 6 having at one end a nut 7 adapted to bear against the outer face of the grip 3 to move it against the action of the spring 8 so that the cam face 85 9 on the upper end of the grip may be moved into and out of engagement with the curved face 10 of an actuating lever 11, pivoted to the rigid lever 2 at 12 and carrying a longitudinally movable jaw stem 13 pivoted 90 thereto by the pivot 14 whereby when the lever 11 is swung about the pivot 14, the movable jaw stem 13 will be reciprocated so that the jaw portion 15 will be moved toward and away from the jaw 1. 95

The actuating lever grip portions 3 and 12 are normally moved in extended positions because the spring 16, fastened to the jaw stem 13 and bearing against the inner face of the grip 11, will tend to force the 100 grip outwardly. When the grip portions 3 and 11 are grasped, however, and squeezed between the fingers, the jaw portion 15 will be moved toward the rigid jaw 1 to grasp the article to be held or pinched, as the case 105 may be.

In order to hold the movable jaw 13 in proper co-operative relation with respect to the jaw portion 1 of the lever 2, a loop or strip 17 is provided, the ends of which are 5 fastened to the jaw 1 as at 18, the loop portion extending about the movable jaw 13 to allow it to freely move longitudinally therein and constitute a guide, as will be clearly apparent by reference to Figs. 1 and 10 3. The right angularly projecting portion 15 constitutes the actual jaw on the member 13 and is provided with a groove 19 in line with the groove 20 in the rigid jaw 1. This is for the purpose of permitting the finger 15 piece 21 to lie in the groove 19 and the nose 20 clamp stem 22 for the nose clamp 23 to lie in the groove 20, the nose clamp 23 being receivable in the transverse groove 24 in jaw 1 and the aligning recess 25 in the jaw stem 13.

The grooves allow the jaws to readily clamp the clamps 26 on the ends of the bridge 27 and cause said clamps to bind upon the grooved frames 28 or 29 to secure 25 the lens in place.

The jaws 1 and 15 are provided with grooves 30 and 31 to provide for the transverse curvature of the frames and the jaws lengthwise are preferably formed on arcs 30 shorter than the arcs from which the curved portions of the clamps 26 are formed so that the ends 32 and 33 of the clamps 26 will be tightly bound upon the frames 28 and 29.

It will be understood, of course, that the 35 mounting may be inverted with respect to the position shown in Fig. 4, if desired, but ordinarily, the clamps 26 will be pinched upon the frames in the position shown although I do not wish to be limited to this 40 particular position of the tool in making the adjustments.

In order to prevent a crushing force being exerted against the clamps 26, I have provided means for adjusting the space between 45 the jaws and this is accomplished by manipulating the nut 7 so that the cam portion 9 of the grip lever 3 will move toward and away from the curved portion 10 of the grip lever 11, the position of the cam 9 determining how close together the jaws can be 50 brought. That is, the closer the upper portion of the grip member 3 is to the lever 2, the further the cam portion 9 will be forced toward the portion 10; therefore, the space 55 will be relatively large, but if the nut is loosened, the cam portion 9 will move away from 10, allowing the grip members 3 and 11 to come closer together and bring the jaws 1 and 2 into closer relation. Therefore, any 60 adjustment between two extremes may be provided.

In connection with the tool I may utilize an expander, shown in Fig. 6 as consisting of the jaw members 34 and 35, pivoted at 36 65 and having expanding portions 37 and 38, to

one of which may be secured supplemental jaw members 39 fastened in any suitable manner so that the jaw member may be renewed, should the occasion demand. The expander shown in Fig. 6 is adapted for 70 spreading the portions preparatory to being clamped so that they can be placed upon the device upon which they are to be pinched to fasten them thereto.

It will be apparent that the device may 75 be modified in construction to suit different conditions without materially departing from the actual invention so I, therefore, do not wish to be limited to the exact details shown.

What I claim and desire to secure by Letters-Patent is:

1. An optician's tool comprising a rigid jaw member having a longitudinal groove and a transverse groove in its outer face 85 parallel with the end of the jaw, and a grooved clamping face at its end, a longitudinally movable jaw member having a groove in its outer face aligning with the longitudinal groove in the rigid jaw member, and means for moving the movable jaw member toward and away from the rigid jaw member in parallel relation thereto.

2. In a tool of the class described, a rigid jaw member comprising an elbow lever, a 95 movable jaw member slideable longitudinally of and co-operating with the rigid jaw member, means for actuating the movable member comprising a lever pivoted to the rigid jaw member and to the movable jaw member, and means for limiting the swinging movement of said pivoted lever comprising a grip member pivoted to the elbow lever and having a cam end movable toward and away from the inner edge of said pivoted 100 lever.

3. In a tool of the class described, a rigid jaw member comprising an elbow lever, a movable jaw member slideable longitudinally of and co-operating with the rigid jaw 110 member, means for actuating the movable member comprising a lever pivoted to the rigid jaw member and to the movable jaw member, means for limiting the swinging movement of said pivoted lever comprising 115 a grip member pivoted to the elbow lever and having a cam end movable toward and away from the inner edge of said pivoted lever, and means for adjusting the grip member comprising a stud projecting 120 through the grip member and a nut on said stud.

4. In a tool of the class described, a rigid jaw member having a longitudinal groove and a transverse groove, a sliding jaw member having a groove aligning with the longitudinal groove in the rigid jaw member and a recess aligning with the transverse groove in the rigid jaw member, and means for actuating the movable member.

5. In a tool of the class described, a rigid jaw member having a transverse groove and a longitudinal groove, a movable jaw member having a grooved portion on one side and a groove on the other side aligning with the longitudinal groove of the rigid jaw member, and a recess in the movable member aligning with the transverse groove in the rigid jaw member.
- 10 6. In a tool of the class described, an elbow lever, a rigid jaw at one end thereof, a pivoted grip device at the other end thereof, a pivoted lever between the grip device and the jaw, a movable jaw member carried thereby, the pivoted lever having a curved 15 inner edge, a cam face on one end of the pivoted grip device, and means for adjusting the pivoted grip device to move the cam toward and away from the inner edge of the pivoted lever. 20

In testimony whereof I affix my signature.
JAMES M. LAWLOR.
